APPARATUS FOR THE TRANSMISSION AT A DISTANCE OF GRAPHICS

Georges Delchef, Brussels, Belgium

Application December 4, 1930, Serial No. 499,881,
and in Belgium December 10, 1929

5 Claims. (Cl. 178—13)

This invention relates to an apparatus for the transmission at a distance of graphics of any kind.

Devices of that kind are known in which contacts making part of a single circuit are displaced substantially in synchronism with respect to transmitting or receiving surfaces.

In those devices, the graphic to be transmitted which is written on a transmitting sheet, for instance of paper, produces variations or interruptions of current, whilst the receiving surface formed of a sheet of sensitive paper is discoloured according to the variations of the transmitting current.

Moreover, it is known to use, as a transmitting and receiving surface, cylinders having a continuous movement of rotation and on each of which a contact is displaced according to a helicoidal path, in such a manner that the surface adapted to be used for the transcription of the message is limited to the peripheral surface of the cylinder.

This inconvenience is particularly important when the user to whom the message is to be transmitted is absent or he is not in a position to control the area of the receiving sheet which remains free for the reception of the messages which are transmitted during his absence. Moreover in view of the difficulty to secure the rotation of the two cylinders which are used as transmitting and receiving surfaces at identical speeds the points touched by the contacts at the same moment on the transmitting cylinder differ from those touched on the receiving cylinder.

My invention has for its object to obviate those inconveniences and to assure by simple means that the receiving apparatus should automatically receive, that is to say, without the user's intervention, a considerable number of successive messages, notwithstanding the absence of a correct synchronism or of identical speeds of displacement, any appreciable distortion of the graphics being practically prevented.

With this object in view, my invention essentially consists in the special arrangements and combinations of parts hereinafter fully described and pointed out in the appended claims.

Referring to the annexed drawings:

Figure 1 is a diagrammatical side elevation of an apparatus constructed according to the present invention.

Figure 2 is an end view of the apparatus.

Figure 3 is an explanatory view showing diagrammatically the several electrical circuits and

the several parts of the apparatus with which these circuits are cooperating.

Figures 4 and 5 show two details of construction.

Figure 6 shows diagrammatically the cooperation of the transmitting and of the receiving apparatus.

In the example shown, the transmitting and the receiving apparatuses are of similar construction, each of them comprises a frame composed of a base 1, of two lateral uprights 2 and 3 which are, preferably obliquely arranged and of an intermediary upright 4.

Between the uprights 2 and 4 a cylinder 5 of conducting material is located and is supported in the said uprights so as to be able to rotate around its longitudinal axis on the one hand in the upright 4 by aid of a trunnion 6 and, on the other hand, by aid of a sleeve 7 resting against the end of a screw 8 mounted in the upright 2.

The several uprights 2, 3 and 4 being arranged obliquely relatively to the base plate 1, the longitudinal axis of the cylinders, as shown in Figure 1, makes an angle with the horizontal direction of the base plate 1 and is in an ascending direction between the uprights 2 and 4.

In front of the cylinder 5 extend two parallel rods 9 and 10 which are mounted in the uprights 2 and 3 and which carry and guide a carriage 11. This latter is provided with a terminal 12 carrying a contact bearer 13, the contact 14 of which is adapted to follow the generatrices of the cylinder 5, when the carriage 11 is displaced along the rods 9 and 10.

Moreover, on the end of cylinder 5 bears a brush 18 connected to a conductor 17 leading to a contact breaker 44—43 which will be described later on, from which a conductor 16 leads to the receiving apparatus wherefrom the current is returned through a conductor 15 in which a source of current, such as a battery S^1 , is inserted, the said conductor 15 being finally connected to the terminal 12 which is in electrical connection through the contact bearer 13 and the contact 14 with the cylinder 5. This electrical circuit is closed through the cylinder 5 each time the contact 14 meets the conducting portions of the graphic, cooperating with this cylinder, provided that a manually operated switch 16¹ inserted in the conductor 15 (see more particularly Fig. 5) has been previously closed,

the contact breaker 44—43 being also closed at this moment as will be hereafter described.

The carriage 11 cooperates with a mechanism which is adapted to produce a partial rotation

of the cylinder 5 on its axis each time the carriage 11 is brought back to its initial or starting position that is to say in its lowest position on the rods 9 and 10.

- 5 To this end, the carriage 11 is provided with a camlike projection 19, cooperating with a lever 20. This lever 20 which carries a pawl 22, acting between the teeth of a ratchet wheel 23, is pivotally mounted at the lower end of the cylinder 5 on an axis 21 and is ended by a lateral projection 26 forming (Fig. 4) an inclined plane 24 cooperating with the projection 19. This lever 20 is further normally maintained in contact by a mass 25¹ with a stop 25 fixed to the base 10 1. When the carriage 11 after having been displaced along the rods 9-10 as will be hereafter explained, is returned to its initial or starting position, the projection 19 slides on the inclined plane 24 and the lever 20 which is displaced in 15 the direction of the arrow A (Fig. 3) is caused to pivot around the axis 21 so as to produce by aid of the pawl 22, acting in the teeth of the wheel 23, the required rotation of the cylinder 5.

In the example shown, it has been supposed 25 that the ascending movement of the carriage is obtained by means of an electric gear comprising an electromotor M (Fig. 3) cooperating with an electromagnetic clutch of any known kind and acting on a pulley 27 (Figs. 1 and 3) to wind up a rope 28 connected to the carriage 11.

The said carriage is further connected by a 30 rope 28¹ to a second pulley 28² which is mounted in suitable brackets on the upright 2. This latter pulley is mounted on a fixed rod 28³ to which it is connected by a spiral spring 28⁴ in such a manner that the said spring is put under tension at each 35 ascending stroke of the carriage 11 along the rods 9 and 10. The upright 3 forms three branches 29¹, 29² and 29³ projecting at right angles, one of 40 which 29³ only is shown in Fig. 1. Two of these branches 29² and 29³ form bearings for a shaft 30 (Fig. 3) on which is keyed the pulley 27 already described.

The shaft 30 is provided at one end with a 45 plate 31 against which bears a spring 32 coiled around the shaft 30 and resting with its other end against a ring 33 embedded in the branch 29².

In alignment with the shaft 30 extends the 50 shaft 34 of the electromotor M mounted on a suitable support (not shown). On this shaft 34 is keyed a plate 35 provided with a distributor 36 as commonly used in electromagnetic clutches; this distributor is inserted in an electric circuit comprising conductors 37 and 37¹ and 55 an electric source S³. The branch 29³ is provided with a projection 38 (Fig. 3) carrying a rod 39 on which is pivotally mounted a rocking lever forming an interrupter, a branch 40 of which lever bears against a disc 42 keyed on the shaft 60 30 and the other branch 41 of which carries a contact 43 which is kept apart from a contact base 44 by a spring 45.

The spring 32 tends to displace the shaft 30 in the direction of the arrow 46 and to keep 65 it in contact with a ball stop 47 carried by the branch 29¹.

In order to assure that the strokes of the carriage 11 take place respectively in the receiving and in the transmitting apparatus within 70 corresponding periods of time, the clutching of the pulley 27 is placed under the control of a chronometrical device or clock work, the general features of which are shown in Fig. 3.

As shown in this figure, this device, the motive 75 part of which is not shown and which may be

a spring actuated chronometer of any suitable construction, is provided with a disc 48 carrying on its periphery a conducting band 49; this disc 48 is mounted on the shaft 50 of the chronometer on which is also mounted a toothed wheel 51 80 gearing (direct or by intermediary wheels not shown) with a toothed wheel 52 fixed on a shaft 53; this wheel 53 further is in mesh with a wheel 54 keyed on a shaft 55.

The disc 48 is provided with a boss 56 co-operating with a projection 57 formed at the end of a lever 58 adapted to pivot on an axle 59 carried by a support 60.

Between the conductors 15 and 16 an auxiliary circuit is formed as shown in Figs. 3 and 90 6. This circuit comprises two conductors 61 and 61¹ bridging the conductors 15 and 16. In one of the said conductors 61 a contact bridge 62 is inserted, this contact bridge being formed by two spring contacts 62¹ (Figs. 5 and 6) between which a projection formed on the disc 48 is engaged when the said disc is at rest. In the second conductor 61¹, an electromagnet 63 is inserted and arranged relatively to the lever 58 so as to attract the said lever, when it is 100 energized and to release the boss 56 of the disc 48 from the projection 57.

The lever 58 carries a contact 64 cooperating with a terminal 65 to which is connected the extremity of a conductor 66 forming part of a circuit including the motor M and a source of electricity such as a battery S³.

On the other hand, on an insulated portion 67 of the band 49 rests when the disc 48 is in its resting position, a blade 68 connected by a conductor 69 to the conductor 66 connecting the battery S³ to the contact 64.

This circuit (S³-66-64-65-66-M-S³) can be closed by the blade 68, the band 49, a brush 70 and a conductor 71 connected to the conductor 66 when the disc 48 is rotated, notwithstanding the interruption at the contact 64.

The wheel 54 comprises an insulated toothed sector 72 and the axles of the wheels 52 and 54 are interposed in the circuit comprising the 120 conductor 37 and 37¹ and the distributor 36 so that the current can only pass through the wheels 52-54 when the insulated sector 72 of the wheel 54 is not in contact with the teeth of the wheel 52.

The device thus constructed works in the 125 following manner:

The sheet carrying the graphic (which is written for instance with an ink adapted to render the transmitting sheet conducting at the spots where the said ink is applied) is wound 130 on a cylinder 5¹ arranged parallelly to the cylinder 5 between the uprights 2 and 4 and adapted to rotate freely. From this cylinder 5¹ it passes to the cylinder 5 on which it is maintained by simple adherence or preferably by little projections meshing with suitable perforations in the marginal portions of the sheet according to the well known method used in cinematographic devices to secure the movement of the film. After having surrounded a portion of the periphery 140 of the cylinder 5, it is guided on a guiding roller 5² from which it remains freely suspended, thus surrounding the cylinder 5 just like a sheet of paper surrounding the roller of a typewriting machine.

At the receiving station a sheet of paper suitably prepared and adapted to be discolored under the influence of the current is similarly passed around a portion of the periphery of the cylinder 5.

The manner of transmitting a message will now be explained with reference to Fig. 6 taken conjointly with Fig. 3. The user of the transmitting apparatus has only to close the switch 16¹.

5 The current of the battery S¹ then flows through the conductor 61 and the contact bridge 62 which is closed the disc 48 of the clock-work being at rest; it then divides between the line conductor 16 leading to the receiving apparatus, 10 and the second conductor 61¹ leading to the electromagnet 63 wherefrom it returns to the battery S¹. The other fraction of the current passing through the line conductor 16 arrives to the receiving apparatus where it is conducted 15 through the conductor 61 of this apparatus and the contact bridge 62 to the electromagnet 63 wherefrom it returns through the conductor 61 to the line conductor 15, and finally to the second pole of the battery S¹. It will be observed that, at this moment both circuit breakers 43—44 are open in such a manner that no current will flow through the cylinders 5 and through the sheets of paper carried thereon. But at the moment that the two electromagnets 63 are thus 20 energized in both apparatus, the discs 48 of the clock-work are released by the oscillating levers 58 which are attracted by the electromagnets 63. As a consequence these discs begin to rotate and the projections on these discs break the circuit 25 passing through the conductors 61 at the contact bridges 62. On the other hand on account of the attraction of the levers 58 by the electromagnet 63 the contacts 64—65 closes thus causing the current of the source S³ to pass 30 through the motor M following first the conductor 66 passing through the contacts 64—65 and returning to the source S³ after having passed through the motor and then, as soon as the disc has made a partial rotation, through the 35 blade 68, the band 49, the brush 70, the conductor 71, to return to the battery S³ through the conductor 66. The rotation of the disc 48 has also as a result to cause the wheels 52—54 to rotate. At the moment that the insulated 40 sector 72 has left the gearing point of the wheels 52—54, the circuit comprising the conductors 37 and 37¹ closes also in such a manner that the current of the source S² is sent through the electromagnetic clutch 35 through the distributor 45 36. The pulley 27 is consequently attracted towards the disc 35; the axle 30 is also displaced in a direction opposite to that of the arrow 46. Consequently the spring 32 is compressed while 50 the circuit breakers 43—44 in each apparatus, pivoting on the axle 39 close the external circuit comprising the conductors 15 and 16.

The current of the battery S¹ will then pass from the battery S¹ through conductor 15 to the terminal 12, the contact bearer 13, the contact 60 14, the cylinder 5 of the transmitting apparatus, line 16, terminal 12 of the receiving apparatus, the contact 14, the cylinder 5, the circuit breaker 44—43 of the receiving apparatus to return to the second pole of the battery S, through the 65 line conductor 15.

The pulley 27 which as already stated has been attracted by the clutch 35 being then rotated, the carriage 11 is drawn upwards along the rods 9 and 10.

70 The current coming from the source S¹ passes then through the conductor 15, the cylinder 5, each time the contact 14 meets a conducting portion of the graphic.

This current impulse reaching the receiving 75 apparatus in the manner described passes

through the receiving sheet and produces a colored point corresponding to the conducting point of the graphic met by the contact of the transmitting apparatus.

During this working of both apparatus the 80 wheels 52—54 are still revolving. After a complete revolution of these wheels the gearing again of the insulated sector 72 causes the cutting off of the circuit S².

The disc 35 no longer being magnetized, the 85 axle 30 is displaced under the action of the spring 32 in the direction shown by the arrow 46; the pulley 27 is thus released and the circuit breaker 43—44 is returned to its starting position thus cutting off the external circuit of 90 the source S¹.

The rotation of the pulley 27 being interrupted the ascending course of the carriage 11 is completed and the latter returns to its starting point under the action of the pulley 28² subjected to 95 the action of the spring 28⁴.

At the end of its descending course, the cam-like projection 19 meets the projection 26, causes the lever 20 to rotate and by aid of the pawl 22 causes the wheel 23 and consequently the cylinder 5 to rotate the value of one tooth of the 100 wheel 22.

Moreover the boss 56 meeting the projection 57 after one revolution of the disc 48, the wheel 48 stops so that all the parts depending from the 105 disc 48 are placed again in the starting position, ready for a further transmission.

As it will be easily understood each revolution of the wheels 52, 54 must correspond to the total of the following times:

(a) The time which is necessary for the carriage 11 to be displaced upwardly a distance corresponding substantially to that of the length of the cylinder 5;

(b) The time which is necessary for the return of the carriage 11;

(c) A stopping time sufficient to compensate the eventual differences in the returning periods.

As a result if in this device differences occur in the displacements during the upward or downward strokes of the carriage 11, these differences cannot be added as indeed the transmission takes place by successive sections, each transmission of one section beginning ineluctably from the same spot. In consequence the carriages may be 120 placed at non-identical speeds which may vary 125 eventually from one transmission to another.

What I claim is:

1. In an apparatus for transmitting and recording graphics, the combination comprising a cylinder mounted to rotate about its longitudinal axis, a contact element cooperating with the cylinder, means for displacing the contact element along the generatives of the cylinder comprising driving means for moving the contact element in one direction only, means for returning the contact element to its initial position, means for partially rotating the cylinder about its axis upon the return of the contact element to its initial position, clutch mechanism for connecting and disconnecting the contact element and the driving means, and clock mechanism for controlling the operation of the driving means.

2. In an apparatus for transmitting and recording graphics, the combination comprising a cylinder mounted to rotate about its longitudinal axis, a movably mounted carriage adapted to be displaced along the generatives of the cylinder, a contact element mounted on the carriage and cooperating with the cylinder, driving means for 145 150

moving the carriage in one direction, means for returning the carriage to its initial position, means for partially rotating the cylinder about its axis upon the return of the carriage to its initial position, a clutch mechanism for connecting and disconnecting the carriage and the carriage moving means, a clock mechanism acting on said clutch mechanism whereby the duration of the displacement of the carriage in one direction under the 10 action of the carriage driving means is dependent upon the clock mechanism.

3. In an apparatus for transmitting and recording graphics, the combination comprising a cylinder mounted to rotate about its longitudinal axis, a movably mounted carriage adapted to be displaced along the generatives of the cylinder, a contact element mounted on the carriage and co-operating with the cylinder, carriage driving means for moving the carriage in one direction only, means for returning the carriage to its initial position, means for partially rotating the cylinder about its axis upon the return of the carriage to its initial position including a ratchet secured to the cylinder and a pawl cooperating therewith and positioned to be actuated upon the return of the carriage, a clutch mechanism for connecting and disconnecting the carriage and the carriage driving means, a clock mechanism acting on the clutching mechanism whereby the 30 duration of the displacement of the carriage under the action of the carriage driving means is dependent upon the clock mechanism.

4. In an apparatus for transmitting and recording graphics, the combination comprising a cylinder mounted to rotate about its longitudinal axis, a movably mounted carriage adapted to be displaced along the generatives of the cylinder, a

contact element carried by the carriage and co-operating with the cylinder, a rotatably mounted pulley, a flexible cable secured to the carriage and the pulley, driving means for rotating the pulley to move the carriage substantially from one end of the cylinder to the other in one direction only, clutching mechanism for connecting and disconnecting the pulley and the driving means, means for returning the carriage to its initial position, means for partially rotating the cylinder upon the return of the carriage to its initial position, a clock mechanism acting on said clutching mechanism and means for placing the duration of the displacement of the carriage under the action of the carriage driving means under 85 the action of the clock mechanism.

5. In an apparatus for transmitting and recording graphics, the combination comprising a cylinder mounted to rotate about its longitudinal axis, a movably mounted carriage adapted to be 95 displaced along the generatives of the cylinder, a contact mounted on the carriage and co-operating with the cylinder, a rotatably mounted pulley, a flexible cable secured to the pulley and the carriage, driving means for rotating the pulley to move the carriage from one end of the cylinder to the other in one direction only, electromagnetic means for connecting and disconnecting the pulley to the driving means, means for returning the carriage to its initial position, means for partially rotating the cylinder about 105 its axis upon the return of the carriage to its initial position, a clock mechanism controlling said electromagnetic means whereby the duration of the displacement of the carriage in one 110 direction is dependent upon the clock mechanism.
